OTTO A. KURT, OF LOS ANGELES, AND SIMPERT C. BARTHOLDI, OF PORTERVILLE, CALIFORNIA.

DISHED-LID CONTAINER.

1,366,265.

Specification of Letters Patent. Patented Jan. 18, 1921.

Application filed April 10, 1920. Serial No. 372,927.

To all whom it may concern:

Be it known that we, OTTO A. KURT and SIMPERT C. BARTHOLDI, citizens of the United States, residing at Los Angeles, in the county of Los Angeles, and Porterville, in the county of Tulare, respectively, and State of California, have invented new and useful Improvements in Dished-Lid Containers, of which the following is a specification.

The object of our present invention is the provision of a dished-lid container of the type in which an opening lever is pivotally attached to the dished lid; the improvement consisting in providing the opening lever with an offset portion adapted when the lever is moved to its working position, to bear solidly on the upper end of the container body, whereby great leverage is afforded and only a slight movement of the lever is necessary to loosen the dished lid and adapt the same to be removed through the medium of the lever. The opening lever is also advantageous, inasmuch as a portion thereof is adapted to bear against the periphery of the dished portion of the removed lid and so that the lever will extend downwardly and outwardly from the lid and render it convenient to handle the said lid through the medium of the lever.

In the accompanying drawings, hereby made a part hereof:

Figure 1 is a vertical section showing the lid as closed and the opening lever in its inner, idle position, said view showing in dotted lines the position in which the opening lever is placed precedent to its employment for the displacement of the lid.

Fig. 2 is a plan view of the same.

Fig. 3 is an elevation illustrating the lid and the opening lever, and also illustrating the bearing of the periphery of the lid against a portion of the opening lever to permit of the lid being conveniently handled through the medium of the lever.

Similar numerals of reference designate corresponding parts in all of the views of the drawings.

The container body 1 is of can form, and is provided with a marginal end flange 2, and an end wall 3 in which is a flanged opening 4. This is the ordinary well known construction, and the lid 5 is also of the ordinary well known construction, being

dished as shown, and provided on its side wall with an outwardly directed flange 6.

In furtherance of our invention, we employ a lid-opening lever 7 that is pivoted to the lid by extending an end portion 8 of the lever through an opening 9 in the flange 6 and bending the said end portion 8 into barrel form so as to form a permanent connection. In addition to the said barrel portion 8, the lever 7 is provided with an offset portion 10 that is adapted in the use of the lever to bear solidly on the end wall 3 of the body. Between the offset portion 10 and the major handle portion 11 of the lever is an intermediate portion 12 disposed approximately at right angles to the major portion, and at the free end of the handle portion 11 is an angularly disposed terminal 13 that extends at an obtuse angle to the handle of lever 7 and is adapted when the lever is in idle position, to extend upwardly from the top of the lid 5, so that the lever may be readily grasped and moved to its working position.

The handle or major portion of the lever 7 bears flat against the lid 5, see full lines in Fig. 1, and hence the portion 10 is adapted to rest flush with the can edge so as not to interfere with another can being superimposed on the can.

When the lever is in its working position (see dotted lines in Fig. 1), the offset portion 10 bears solidly on the end of the body, and therefore when downward pressure is exerted on the outer end of the handle portion 11, the lid 5 is strongly displaced.

After the displacement of the lid 5 as stated, the operator retains his hold on the lever 7, whereupon the lid 5 will bear against the offset portion 10 of the lever (see Fig. 3), and therefore the lid may be conveniently handled through the medium of the lever, and may be readily restored to its position in the end wall of the body. Again when the lid is restored to its closed position as stated, the lever 7 may be swung back to its original idle position, shown by full lines in Fig. 1, so as to be out of the way.

Having described our invention, what we claim and desire to secure by Letters-Patent, is:

A dished-lid container of lid-opening lever type, comprising a container body having an end wall within and spaced from its end

and in which is an opening spaced from the side wall of the container, a dished lid removably arranged in said opening of the body, and an opening lever pivotally connected to the edge of the dished lid and movable from within the lid to an outwardly and downwardly extending position outside the same and vice versa, and having adjacent to the pivotal connection an offset portion arranged to fulcrum against the end of the body and also having a major handle portion and an approximate right angle portion intermediate of the offset portion and the handle portion; the said handle portion being straight and having at its free

end an obtuse-angle terminal adapted when the handle portion is in its inner idle position flat on the top of the lid to permit the offset portion to rest flush with the can edge, to extend upwardly from the lid, and the offset portion being arranged when the lever is swung outwardly and downwardly to bear against the outer side of the dished portion of the lid and enable the lever to serve as a handle for the lid.

25

In testimony whereof we affix our signatures.

OTTO A. KURT.
SIMPERT C. BARTHOLDI.
